SPINNING DISK WITH EMBOSSED INDICIA

Frank E. Seale, Lexington, Ky., assignor to V. P. Seale, doing business as Bill-E-Company, Lexington, Ky.

Application July 11, 1951, Serial No. 236,166

1 Claim. (Cl. 46—64)

1 The present invention relates to certain new and useful improvements in spinning devices and has more particular reference to a unique spinning disk or token with embossed indicia and other novel characteristics.

Stated somewhat more specifically, the invention appertains to rotatable game pieces and perhaps, in a remote way, to spinning tops. However, and precisely speaking, it is neither of these but takes the form of what may be conveniently called a lucky pocket-piece. It ranges in diameter or size from that of a half-dollar or a dollar-piece and may be carried about in one's pocket as a souvenir, keepsake, or, as above stated, as a good luck pocket-piece.

One object of the invention is to provide a pocket-piece which has remarkable balance and free spinning properties and has flat top and bottom faces provided with embossments which may be used so that one face provides advertising media for the sponsor and the other face provides schedules for football games, basketball games and similar events and activities. Thus used as a token the disk becomes a practical permanent advertisement for those who sponsor it and give it free of charge to their customers.

Another object of the invention, primarily from a structural point of view, has to do with a manually twirled spinning-type pocket-piece which takes the form of a disk of a diameter to be conveniently grasped in one's finger and spun, in familiar fashion, into rotation, said disk having flat obverse and reverse faces, being of lightweight metal such as aluminum and being provided on its bottom or reverse face with an axially centered spindle, said spindle being relatively short so that the stated reverse face sweeps the supporting surface, a table or the like, with a minimum of clearance, thus limiting the tendency of the disk to wobble and promoting prolonged spinning results.

A still further object is to provide a disk having the aforementioned structural characteristics and which is also provided on its top or obverse face with an indicating arrow denoting the stopping place of the disk when the momentum gives out and the disk comes to a standstill, said arrow being situated in close proximity to the periphery of the disk and serving as a pointer.

Other objects and advantages will become more readily apparent from the following description and the accompanying sheet of illustrative drawings.

In the accompanying sheet of drawings where-

in like numerals are employed to designate like parts throughout the views:

Figure 1 is a view showing a fragmentary portion of a table or the like, showing the disk resting thereon and showing the manner in which it is adapted to be spun for tell-tale and other purposes;

Figure 2 is an enlarged top plan view of the spinning disk showing what is hereinafter referred to as the flat obverse face of the same;

Figure 3 is a bottom plan view of the reverse face thereof; and,

Figure 4 is an exaggerated central section taken on the plane of the line 4—4 of Figure 2, looking in the direction of the arrows.

The spinning disk as an entity is denoted by the numeral 6 and in practice it is preferably light in weight and usually constructed from aluminum. As a general practice the disks in use range from the size of a half-dollar to a silver-dollar, although the factor of size is more-or-less optional. Generally speaking, the disk should be of a size to permit it to be conveniently grasped between the thumb and index and second fingers as shown in Figure 1, in order that it may be easily twirled in a familiar manner and thus spun, let us say, in the direction of the arrow in Figure 1. The top or obverse face is perfectly flat and denoted at 8 and the bottom or reverse face 10 is likewise flat. The peripheral edge of the disk is circumscribed by an annular rim 12 having its upper and lower marginal edge portions defining flanges 14 and 16 respectively. There is an extruded spindle at the exact axial center of the disk and this is denoted by the numeral 18 and has a pin-point pivot 20. The extrusion step leaves an indentation as at 22 which is of no moment, functionally speaking. Both faces 8 and 10 are provided with predetermined embossments and these vary in nature although all the embossments are within the confines of the flanges 14 and 16 and generally speaking between the same and the spindle 18. Looking at Figure 2, the principal embossment is a pointer or indicating arrow 24 and this is situated adjacent to the flange 14 and is radial and functions to denote, obviously, the stopping point of the disk after the momentum has stopped and the disk has come to a standstill. Diametrically opposite to the indicating arrow is an embossed symbol which in the instant showing is a four-leaf clover 26 companion to the adage "Good Luck" 28 which happens to be on the arrow side. The in-between embossments or indicia denoted at 30 may be classified as suitable advertising media. The reverse or

bottom side 10 displays other embossments denoted generally by the numeral 32 and these may be football schedules, basketball schedules and other messages of a timely nature and arranged chronologically or otherwise.

It will be understood that the subjects-matter covered by the various indicia embossments is, of course, not fixed and the description of same is not limiting. Generally speaking, however, the obverse face 8 will invariably carry a pointer such as the arrow 24, an ad of a suitable type and some message of surpassing merit that the disk may be classified as a charm or lucky pocket-piece. The arrow 24 is significantly important in that it denotes the stopping point or place after the disk has been spun and comes to a standstill. The disk may be used on a card table for selecting a dealer for example; or, may be used in a refreshment parlor or restaurant to "pick" the person who, as a result of the spinnings, is designated to pay for the meal and so on. The information constituting the indicia 32 on the reverse side is purely for informative purposes, as is obvious.

The essence of the invention is in the construction shown in Figure 4 wherein it will be observed that the surfaces of the embossments 32 are all in the same plane and in a plane with line A. The surfaces of the edges or flanges 16 are on a lower plane represented by the character B and the pivot point of the spindle, the point 20, occupies the plane C. It is clear, therefore, that the disk is suspended by the pivot point from the surface D of the table and, so supported, causes the embossments 39 and edges 16 to clear the table surface. This disk is precision made and uniformly balanced and rotates with amazing speed when set into rotation by the hand of the user. When forcibly twirled and spun on a perfectly flat and smooth table or equivalent surface the disk twirls speedily and continues to spin for a considerable time, thus providing an article which is both unique and therefore a novelty spinning-type pocket-piece.

The indicator arrow 24 need not necessarily be an "arrow." That is to say, it may be an embossed soft drink bottle or a milk bottle represented in order to inject the idea of "spin the bottle."

Minor changes in the shape, size, material and arrangement of parts may be resorted to in actual practice without departing from the spirit and scope of the invention, as claimed.

5 Having described the invention, what is claimed as new is:

A manually twirled spinning-type pocket-piece used primarily for advertising purposes and comprising a light weight non-corrosive disk of 10 a diameter to be conveniently grasped in one's fingers and spun into motion on a table or other support surface, said disk having planar obverse and reverse faces, said obverse face being centrally depressed to provide a spindle with a pivot 15 point for the reverse face, said spindle projecting beyond said reverse face a relatively short distance in comparison with the area of said disk, whereby said reverse face sweeps the support surface with a minimum of clearance, thus limiting the tendency of the disk to wobble and drag while spinning, said disk having a peripheral rim with upper and lower marginal edges projecting above and below the respective obverse and reverse faces to minimum degrees, and 20 25 30 35 the pivot point of said spindle projecting to a plane slightly below the plane of the lower marginal edge of said rim to cause the latter to clear the support surface with requisite clearance, and said reverse face having indicia embossments thereon in the area between said spindle and lower marginal edge, said embossments all being in the same plane, a plane which is higher than the plane occupied by said lower edge.

FRANK E. SEALE.
